DESIGN FOR A JEWELRY FINDING FOR PINS OR THE LIKE

Earle L. Morrow, Johnston, R. I., assignor to
Frank Morrow & Co. Inc., Providence, R. I., a
corporation of Rhode Island

Application May 1, 1936, Serial No. 62,416

Term of patent 3½ years

To all whom it may concern:

Be it known that Earle L. Morrow, a citizen
of the United States, residing at Johnston, in
the county of Providence and State of Rhode
Island, has invented a certain new, original,
and ornamental Design for a Jewelry Finding
for Pins or the like, of which the following is
a specification reference being had to the ac-
companying drawing, forming a part thereof:

Fig. 1 is a plan view of a jewelry finding for
pins or the like embodying my new design.

Fig. 2 is a side elevation thereof.

Fig. 3 is an end elevation thereof.

I claim:

The ornamental design for a jewelry finding
for pins or the like substantially as shown.

EARLE L. MORROW.
